UNITED STATES PATENT OFFICE.

CARL A. WENDELL, OF JOLIET, ILLINOIS.

DRIER.

1,244,007.

Specification of Letters Patent. Patented Oct. 23, 1917.

Application filed June 12, 1915. Serial No. 33,791.

To all whom it may concern:

Be it known that I, CARL A. WENDELL, a citizen of the United States, residing at Joliet, in the county of Will and State of Illinois, have invented a certain new and useful Improvement in Driers, of which the following is a specification.

My invention relates to a process for drying granular or lump material, such for example, as coal. It consists broadly in rotating a mass of such material arranged in the shape of a ring so that the moisture or water will be expelled therefrom by centrifugal force, and at the same time discharging successive dried sections of said ring of material by centrifugal force and feeding successive sections of moist material to the parts of the ring so left vacant by the expulsion of the dried section. There are many apparatuses and devices whereby the process can be carried out, but in one form of apparatus the ring of material is formed upon an annular perforated screen through which the water is expelled, while wet material is furnished to the ring by a spout, the spout and ring rotating in the same direction at different speeds. By successively discharging a dry section from the ring and immediately thereafter supplying from the spout a like section of wet material, the ring is kept practically intact and becomes in effect a constantly moving mass of material at various stages of dryness, rotating across the path along which the wet material is fed to the inside of the ring and the dry material discharged from the outside thereof. Such an arrangement must have means whereby the water is carried off in one direction and the dried material is discharged in another direction.

For the purpose of illustrating my invention, I have employed a diagrammatic drawing wherein—

Figure 1 is a diagrammatic plan view, 45 and

Fig. 2 a diagrammatic cross section of an apparatus by which my process could be carried out.

Like parts are indicated by similar letters 50 in all the figures.

A is a hopper from the lower part of which leads a spout B.

C is a ring of coal banked up against an inclined annular screen D.

The ring and the spout are rotated in the 55

same direction as indicated by the large arrow in Fig. 1, but differentially, the spout a little faster than the ring.

E is a pair of small arrows indicating the flow of coal or material through the 60 spout outwardly toward the ring, and E¹ a pair of similar arrows indicating the flow of such material from the end of the spout toward the ring. It is obvious that if the supply be continuous, and the ring and 65 spout are thus rotated, the spout faster than the ring, but both continuously in the same direction, the tendency will be to supply a small continuous flow of material to the ring. The ring and spout should rotate 70 rapidly so that the water may be expelled from the coal or material in the screen, and it may pass on into the channel F. E² indicates a pair of arrows showing the direction of movement of the ring-shaped mass 75 of coal.

G is a trap door below the screen D, and there should be one of these for each of a predetermined number of sections of the 80 floor which holds the ring of material. Means are provided whereby these traps are successively opened to allow a dried section of the ring of material just in advance of the point where the spout is delivering 85 to the ring, to be discharged by centrifugal force outwardly, and then downwardly into the receiving hopper, H, as indicated by the pairs of small arrows E³, E⁴.

I have not, of course, endeavored to show 90 a mechanism, but have simply contented myself with suggesting diagrammatically one form of structure which might be used, but there are many others. Broadly speaking, the process consists in feeding the coal in a flowing stream to successive suctions 95 of a ring of material, which ring of material ceases to flow but rotates as a mass until the water has been expelled, and then discharging successive dried sections of the coal from the ring in a flowing stream such 100 discharge of water and coal from the ring being substantially continuous, and effected by centrifugal force. If the spout is moved slower than the ring of material then the dumping means must be provided to dump 105 behind the discharge spout stated in terms of its movement with respect to the ring of material. In either event, however, the dumping takes place before or in advance 110 of the discharge of material to be dumped.

or empty portion of the ring, that is to say, the ring is first cleared of material at a certain point and then subsequently wet material is added to that point. In the 5 claims I have described the discharged section as being in advance of the fed section, that is to say, the discharged section is always dumped before the feeding spout reaches the position from which it discharges wet material to the previously 10 emptied zone.

In the particular mechanism diagrammatically illustrated and proposed as a means of working my process, I may further 15 explain that the trap doors G serve to arrest or prevent the discharge of the several sections of the annulose or annular mass of material and that they are successively operated each to release a given section and 20 permit centrifugal force to discharge it when said section shall have been sufficiently dried. There is no effective operation of these doors when the machine is at rest, but when the basket is in motion the spout 25 travels differentially with reference to the basket and is associated with a door tripping mechanism, so that each section when filled will travel a considerable period before the differential action will cause the arm to 30 open the door and permit the dried material to escape, but there is during action at all times a steady discharge of successive sections of the material as it is dried, and a steady filling of such successive sections 35 the moment they are discharged.

In Figs. 3 and 4 the gate opening means are shown in detail. It will be observed that the spout B carries an arm F. This arm carries a cam F¹, which is in opposition 40 to the arm F². This arm passes upwardly through a hole F³ in the floor of the hopper, and supports at its bottom a weight F⁵. This weight is on one end of a bell crank lever F⁶ pivoted at the bottom of the hopper or drying chamber, and carrying or supporting the pivotally mounted trap door G. It will be clear that as the chute and the 45 drying chamber rotate differentially, the cam on the arm will lift successively the weights holding the pivoted trap door shut, thus permitting material to successively pass out from beneath the screen through the successively opened trap doors.

I claim:

55 1. The process of drying granular or lumpy material, which consists in feeding the same by a flowing stream to successive sections of an annular mass of the material, rotating such annular mass to expel the 60 water therefrom by centrifugal force, and discharging by centrifugal force successive sections of the dried material in an outwardly flowing stream, the discharged section being just in advance of the section 65 which is being fed.

2. The continuous process of drying granular or lumpy material which consists in feeding the same by a continuously flowing stream to successive sections of an annular mass of the material, rotating such annular mass continuously to expel the water therefrom by centrifugal force, and continuously discharging by centrifugal force successive sections of the dried material in an outwardly flowing stream, the discharged section being just in advance of the section 75 which is being fed.

3. The process of drying granular or lumpy material, which consists in feeding the same by a flowing stream to successive 80 sections of an annular mass of the material, rotating such annular mass through a large number of complete revolutions to expel the water therefrom by centrifugal force, and discharging by centrifugal force successive 85 sections of the dried material in an outwardly flowing stream.

4. The continuous process of drying granular or lumpy material, which consists in feeding the same by a continuously flowing 90 stream to successive sections of an annular mass of the material, rotating such annular mass through a large number of complete revolutions continuously to expel the water 95 therefrom by centrifugal force, and continuously discharging by centrifugal force successive sections of the dried material in an outwardly flowing stream.

5. The process of drying granular or lumpy material, which consists in feeding 100 the same by a flowing stream to successive sections of an annular mass of the material, holding in opposition against centrifugal force and rotating such annular mass to expel the water therefrom by centrifugal force, and discharging by centrifugal force successive 105 sections of the dried material in an outwardly flowing stream, the discharged section being constantly replaced by the section 110 which is being fed.

6. The continuous process of drying granular or lumpy material which consists in feeding the same by a continuously flowing stream to successive sections of an annular mass of the material, holding in position 115 against centrifugal force and rotating such annular mass continuously to expel the water therefrom by centrifugal force, and continuously discharging by centrifugal force successive sections of the dried material in an 120 outwardly flowing stream, the discharged section being constantly replaced by the section which is being fed.

7. The process of drying granular or lumpy material, which consists in feeding 125 the same by a flowing stream to successive sections of an annular mass of the material holding in position against centrifugal force and rotating such annular mass through a large number of complete revolutions to ex- 130

- pel the water therefrom by centrifugal force, and discharging by centrifugal force successive sections of the dried material in an outwardly flowing stream.
- 5 8. The continuous process of drying granular or lumpy material, which consists in feeding the same by a continuously flowing stream to successive sections of an annular mass of the material, holding in position 10 against centrifugal force and rotating such annular mass through a large number of complete revolutions continuously to expel

the water therefrom by centrifugal force, and continuously discharging by centrifugal force successive sections of the dried material in an outwardly flowing stream.

In testimony whereof, I affix my signature in the presence of two witnesses this 24th day of May, 1915.

CARL A. WENDELL.
